UNITED STATES PATENT OFFICE.

JOB C. BARTLETT, OF PITTSBURG, PENNSYLVANIA, ASSIGNOR TO THE J. C. BARTLETT COMPANY, OF SAME PLACE.

DESIGN FOR A CROSSPIECE FOR STOVE OR RANGE LIDS.

SPECIFICATION forming part of Design No. 34,147, dated February 26, 1901.

Application filed October 20, 1900. Serial No. 33,784. Term of patent 14 years.

To all whom it may concern:

Be it known that I, JOB C. BARTLETT, a resident of Pittsburgh, in the county of Allegheny and State of Pennsylvania, have invented and produced a new and original Design for Cros-
5 pieces for Stove or Range Lids; and I do hereby declare the following to be a full, clear, and exact description thereof, reference being had to the accompanying drawings, in which—

10 Figure 1 is a top view of a crosppiece for stove and range lids embodying my design. Fig. 2 is a cross-section thereof on the line 2 2, Fig. 1; and Fig. 3 is a bottom view of the same.

15 The leading feature of my design consists in a crosppiece for stove and range lids having the shape and form substantially as herein shown and described.

20 As illustrated in the drawings, 10 repre-
sents the crosppiece, which is provided with the lifter-opening 11, extending down into the same from the face 12 thereof. Extending into the crosppiece are the semicircular openings 13, which are provided with the

25 curved rims or flanges 14 around the openings 13 and provided with straight portions 15 thereon, so as to form seats 16. Projecting out from each of the curved edges 12' of the body portion 12 of the crosppiece 10 opposite the straight portions 15 are the lugs 17, which 30 are formed as part of and rest upon the rims or flanges 14 and are provided with the angular ends 18 thereon.

Having described my invention, what I claim as new, and desire to secure by Letters 35 Patent, is—

The design for a crosppiece for stove and range lids, substantially as herein shown and described.

In testimony whereof I have signed my 40 name to this specification, in the presence of two subscribing witnesses, at Pittsburgh, in the county of Allegheny and State of Pennsylvania, this 17th day of October, 1900.

JOB C. BARTLETT.
